UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

CORRUGATED METALLIC WALL PLATE.

Application filed August 30, 1926. Serial No. 132,622.

My invention relates to the construction of railway cars and more particularly to metal end structures or walls for railway cars made of one or more metallic plates or panels formed with integral reinforcing, stiffening and bracing embossments or corrugations.

It is well known that the end walls of railway cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency.

One of the principal objects of my invention is to provide a corrugated metallic end structure for railway cars in which the corrugations have a configuration and arrangement that impart to the structure a maximum capacity for resisting cargo thrusts, both local and general, static or quiescent, and with sufficient resiliency to prevent permanent distortion due to the thrusts of the loads, with a minimum weight of metal. It is important that structures of this sort should be as light as possible, consistent with strength and durability, both for reasons of economy in manufacturing cost and also to keep the weight of the car at a minimum.

A further object is to provide a corrugated metallic wall element that is practically possible to manufacture. A further object is to provide a metallic wall element with corrugations that resist to a greater degree torsional stresses, as well as brace the element, and the car end against diagonal side thrusts or weavings.

The combination of the embossments, ribs or corrugations comprising the reinforcement formed in the metallic plate is disclosed and claimed in my separate application for patent, Serial No. 595,632, filed October 19, 1922, and my application Serial

No. 132,621, filed August 30, 1926; discloses and claims the specific advantages and constructions wherein the corrugations are positioned vertically.

In the drawings:

Fig. 1 shows the end wall of a railway box car with my device applied thereon.

Fig. 2 is a section on line 2—2 of Fig. 1.

Fig. 3 is similar to Fig. 2 but shows a modified form.

Fig. 4 is a section on line 4—4 of Fig. 1.

Fig. 5 is a section on line 5—5 of Fig. 1.

Fig. 6 shows the end wall of a railway gondola car with my device applied thereon.

Figs. 7 to 10 inclusive are sections on lines 7, 8, 9 and 10, respectively, of Fig. 6 with the car parts omitted.

The end wall structure shown in the above figures comprises a panel composed of a corrugated metal plate or plates.

Referring to Figs. 1 to 5, inclusive. The corrugated plates 31, 32 and 33 extend across the car from top to bottom and are formed with integral flanges 4 along the vertical edges which overlap and are secured to the side walls 5 of the car by any suitable means.

The top edge of the end wall is secured beneath the fascia boards 27 and the meeting edges of the plate overlap and are secured together by rows of rivets 28 and the lower edge of the end wall is secured to the end sill 29. Nailing strips 10 are secured to the plates 31, 32 and 33 by bolts and lining 11 is secured to the nailing strips 10. The embossments decrease in depth from their ends towards their middle portion. In this arrangement the wall is very strong adjacent the floor of the car and very elastic at a predetermined place (preferably one-third from the lower ends of the embossments) and also is very strong adjacent the roof of the car.

Fig. 6 shows a modified form of the invention applied to a gondola type of car, wherein only one plate 12 is used to form the end panel which extends from side to side of the car and is provided along the vertical edges with flanges 13 which overlap and are secured to the side walls 14 by any suitable means. The top edge of the plate is secured to the top chord 15 by rivets 16, while the lower edge is secured by rivets 17 to the end sill 18. In this arrangement the embossments are positioned horizontally.

that the wall is very strong adjacent the side walls of the car and very elastic adjacent the middle of the car.

Figs. 7 to 10 inclusive are sections on lines 5 7, 8, 9 and 10, respectively, with the parts of the car omitted. Numeral 1 is the plate; 2 the plane of the plate; 5 is the major corrugation that forms the principal stiffening and rigidifying element; 6 is the valley formed between the major corrugations; 7 is the minor corrugation that sets within the major corrugation 5; 8 is the extremity of the corrugation and 9 is the flat apex of the major corrugation.

15 The major corrugations are relatively deeper adjacent their ends and decrease in depth toward their middle and are also preferably relatively narrow adjacent their ends and increase in width toward their middle. In the preferred form the line of minimum depth is near the line of maximum width.

20 Fig. 3 shows a modified form wherein the corrugation is deeper adjacent its lower end than adjacent its upper end and the minor corrugation is of constant depth the major portion of its length.

25 The construction may also be described as a plurality of corrugations which merge into each other adjacent their ends. These corrugations are spaced apart distances equal to their width so as to form a symmetrical cross section about a line midway between their outermost portions, thereby obtaining 30 the maximum amount of strength for a minimum amount of steel in the plate. The merged ends form a corrugation which is preferably relatively wider and deeper and such corrugations (merged ends) are also 35 symmetrical in cross section about a line midway between their outermost portions.

40 The structure is designed to be formed between dies which move toward each other in one direction only, therefore, to facilitate 45 pressing by equally distributing the stretching of the metal the corrugations are so formed that the length of the center line of the metal of every cross section normal to the corrugations are equal, i. e., between the 50 terminal portions.

55 The embossments or corrugations are preferably of constant width and depth equi-distant on opposite sides of their center to provide die adjustment for different length corrugations.

60 While the corrugations are shown pressed outwardly, it is understood that the corrugations may be pressed inwardly, or partially inwardly and partially outwardly, from the original plane of the plate. The plates or panels may be applied to any type of railway car.

65 Metallic plates corrugated as described wherein a plurality of corrugations merge into a contiguous, sinuous and uniform con-

figuration possess the advantage of great strength and elasticity and (by merging the corrugations together at their extremities) simplifies the termination into the original plane and margins of the plate resulting in 70 a plate of comparatively little weight of maximum strength and one that is easy to manufacture. Although the figures disclose a plurality of sinuous corrugations merging together, it is to be understood that my 75 invention is not limited to this particular configuration but the corrugations at this point may be of any cross section.

By thus forming a metallic plate I provide 80 a plurality of corrugations or beams which cooperate to form a very strong structure capable of absorbing considerable stress without much deflection and which also form a resilient structure below the center of the corrugations so that when the plate deflects under extreme load it rebounds or returns to its normal position without appreciable permanent distortion.

This application is confined to the construction wherein the major corrugation is 85 split into two or more minor corrugations, while my application Serial No. 595,631, filed October 19, 1922, on metal end structures for railway cars covers a construction 90 wherein the minor corrugations merge to 95 form the major corrugation.

While the drawings shown only two reinforcements in each plate, it is understood that any number of such reinforcements may be formed in an individual plate or the 100 panel structure may be composed of a plurality of plates secured together, each of such plates having one or more such reinforcements formed therein.

The accompanying drawings illustrate the 105 preferred form of the invention, though it is to be understood that the invention is not limited to the exact details of construction shown and described, as it is obvious that various modifications thereof within the 110 scope of the claims will occur to persons skilled in the art.

I claim:

1. A metallic plate provided with a plurality of corrugations symmetrical in cross section about a line midway between their outermost portions which merge into each other adjacent their ends to form a plurality of wider corrugations symmetrical in cross section about a center line midway between 115 their outermost portions, said corrugations decreasing in depth from their ends towards their middle portion.

2. A metallic plate provided with a plurality of corrugations spaced apart distances substantially equal to their width, said corrugations merging adjacent the ends of the plate into a lesser number of corrugations 120 spaced apart distances substantially equal to their width, said corrugations decreasing in 125

depth from their ends toward their middle portion.

3. A metallic plate provided with a plurality of corrugations spaced apart distances substantially equal to their width, said corrugations merging adjacent the ends of the plate into a lesser number of wider corrugations spaced apart distances substantially equal to their width, said corrugations decreasing in depth from their ends toward their middle portion.

4. A metallic plate wall element provided with a plurality of corrugations spaced apart distances substantially equal to their width, said corrugations merging adjacent the ends of the plate into a lesser number of wider corrugations, said corrugations decreasing in depth from their ends toward their middle portion.

5. A metallic plate wall element provided with a plurality of corrugations which merge into each other adjacent their ends into a lesser number of corrugations, said corrugations decreasing in depth from their ends toward their middle portion.

6. A metallic plate wall element provided with a plurality of corrugations which merge into each other adjacent their ends into a lesser number of wider corrugations, said corrugations decreasing in depth from their ends toward their middle portion.

7. A metallic plate wall element provided with a plurality of corrugations which merge into each other adjacent their ends into a lesser number of wider corrugations, said corrugations decreasing in depth from their ends toward their middle portion, the length of the center line of the metal being equal at every cross section of the corrugated portion of the plate normal to the corrugations.

8. A metallic plate provided with a plurality of reinforcements comprising a plurality of shallow stiffening ribs which merge into each other adjacent the ends of said reinforcements to form a plurality of deeper stiffening ribs, the length of the center line of the metal of the cross section of the shallow corrugations being substantially equal to the length of the center line of the metal of the cross section of the deeper corrugations.

9. A metallic plate provided with a plurality of corrugations spaced apart distances substantially equal to their width, said corrugations merging adjacent the ends of the plate into a lesser number of wider and deeper corrugations spaced apart distances substantially equal to their width.

10. A metallic plate provided with a plurality of corrugations merging adjacent the ends of the plate into a lesser number of wider and deeper corrugations.

11. In a railway car structure, a metallic plate formed with a plurality of corruga-

tions which have their middle portions divided so as to provide a relatively rigid structure adjacent the ends of the corrugations and a relatively resilient structure adjacent the middle of the corrugations.

12. In a railway car structure, a metallic plate formed with a plurality of corrugations which have their middle portions divided so as to provide a relatively rigid structure adjacent the ends of the corrugations which gradually becomes a relatively resilient structure adjacent the middle of the corrugations.

13. In a railway car structure, a metallic plate formed with a plurality of corrugations which are relatively deep adjacent their end portions, said corrugations having their middle portions divided to form a greater number of relatively shallow corrugations adjacent their middle portions so as to provide a relatively rigid structure adjacent the end of the corrugations and a relatively resilient structure adjacent the middle of the corrugations.

14. In a railway car structure, a metallic plate formed with a plurality of corrugations which are relatively deep adjacent their end portions, said corrugations having their middle portions divided to form a greater number of relatively shallow corrugations adjacent their middle portion so as to provide a relatively rigid structure adjacent the end of the corrugations which gradually becomes a relatively resilient structure adjacent the middle of the corrugations.

15. In a railway car structure, a metallic plate formed with a plurality of corrugations which are relatively deep and relatively wide adjacent their end portions, said corrugations having their middle portions divided to form a greater number of relatively shallow and relatively narrow corrugations adjacent their middle portions so as to provide a relatively rigid structure adjacent the end of the corrugations and a relatively resilient structure adjacent the middle of the corrugations.

16. In a railway car structure, a metallic plate formed with a plurality of corrugations which are relatively deep and relatively wide adjacent their end portions, said corrugations having their middle portions divided to form a greater number of relatively shallow and relatively narrow corrugations adjacent their middle portions so as to provide a relatively rigid structure adjacent the end of the corrugations which gradually becomes a relatively resilient structure adjacent the middle of the corrugations.

17. A wall for a railway car comprising a metallic plate secured to oppositely disposed frame members of the car, said plate provided with a plurality of corrugations merging into each other and terminating into the plate adjacent said oppositely dis-

posed frame members to form a lesser number of corrugations.

18. A wall for a railway car comprising a metallic plate secured to oppositely disposed frame members of the car, said plate provided with a plurality of corrugations merging into each other and terminating into the plate adjacent said oppositely disposed frame members to form a lesser number of wider corrugations.

19. A wall for a railway car comprising a metallic plate secured to oppositely disposed frame members of the car, said plate provided with a plurality of corrugations merging into each other and terminating into the plate adjacent said oppositely disposed frame members to form a lesser number of wider and deeper corrugations.

20. A wall for a railway car comprising a metallic plate secured to oppositely disposed frame members of the car, said plate provided with a plurality of corrugations spaced apart distances substantially equal to their width, said corrugations merging into each other and terminating into the plate adjacent said oppositely disposed frame members to form a lesser number of corrugations spaced apart distances substantially equal to their width.

21. A wall for a railway car comprising a metallic plate secured to oppositely disposed frame members of the car, said plate provided with a plurality of corrugations spaced apart distances substantially equal to their width, said corrugations merging into each other and terminating into the plate adjacent said oppositely disposed frame members to form a lesser number of wider corrugations spaced apart distances substantially equal to their width.

22. A wall for a railway car comprising a metallic plate secured to oppositely disposed frame members of the car, said plate provided with a plurality of corrugations spaced apart distances substantially equal to their width, said corrugations merging into each other and terminating into the plate adjacent said oppositely disposed frame members to form a lesser number of wider and deeper corrugations spaced apart distances substantially equal to their width.

23. A wall for a railway car comprising a metallic plate secured to oppositely disposed frame members of the car, said plate provided with a plurality of corrugations symmetrical in cross section about a line midway between the outermost portions of the corrugations, said corrugations merging into each other and terminating into the plate adjacent their oppositely disposed frame members to form a lesser number of corrugations symmetrical in cross section about a line midway between the outermost portions of the corrugations.

24. A wall for a railway car comprising a

metallic plate secured to oppositely disposed frame members of the car, said plate provided with a plurality of corrugations symmetrical in cross section about a line midway between the outermost portions of the corrugations, said corrugations merging into each other and terminating into the plate adjacent their oppositely disposed frame members to form a lesser number of wider corrugations symmetrical in cross section about a line midway between the outermost portions of the corrugations.

25. A wall for a railway car comprising a metallic plate secured to oppositely disposed frame members of the car, said plate provided with a plurality of corrugations symmetrical in cross section about a line midway between the outermost portions of the corrugations, said corrugations merging into each other and terminating into the plate adjacent their oppositely disposed frame members to form a lesser number of wider and deeper corrugations symmetrical in cross section about a line midway between the outermost portions of the corrugations.

26. A wall for a railway car comprising a metallic plate secured to oppositely disposed frame members of the car, said plate provided with a plurality of corrugations merging into each other and terminating into the plate adjacent said oppositely disposed frame members to form a lesser number of deeper corrugations, the length of the center line of the metal of a cross section of the shallower corrugations being substantially equal to the length of the center line of the metal of a cross section of the deeper corrugations.

27. A wall for a railway car comprising a metallic plate secured to oppositely disposed frame members of the car, said plate provided with a plurality of corrugations merging into each other and terminating into the plate adjacent said oppositely disposed frame members to form a lesser number of wider and deeper corrugations, the length of the center line of the metal of a cross section of the shallower corrugations being substantially equal to the length of the center line of the metal of a cross section of the deeper corrugations.

28. A wall for a railway car comprising a metallic plate secured to oppositely disposed frame members of the car, said plate provided with a plurality of continuous sinuous corrugations merging into each other and terminating into the plate adjacent said oppositely disposed frame members to form a lesser number of corrugations with substantially flat apices.

29. A wall for a railway car comprising a metallic plate secured to oppositely disposed frame members of the car, said plate provided with a plurality of contiguous sinuous corrugations merging into each other and

terminating into the plate adjacent said oppositely disposed frame members to form a lesser number of wider corrugations with substantially flat apices.

5 30. A wall for a railway car comprising a metallic plate secured to oppositely disposed frame members of the car, said plate pro-

vided with a plurality of contiguous sinuous corrugations merging into each other and terminating into the plate adjacent said oppositely disposed frame members to form a lesser number of wider and deeper corrugations with substantially flat apices. 10

ARTHUR E. SMALL.
